R. A. FESSENDEN,
METHOD OF DESTROYING ENEMY GUN POSITIONS,
APPLICATION FILED DEC. 8, 1919.

1,384,030.

Patented July 5, 1921.

METHOD OF DESTROYING ENEMY GUN POSITIONS.

1,384,030.

Specification of Letters Patent.

Patented July 5, 1921.

Original application filed January 11, 1919, Serial No. 270,723. Divided and this application filed December 8, 1919. Serial No. 343,241.

To all whom it may concern:

Be it known that I, REGINALD A. FESSENDEN, of Newton, in the county of Middlesex and State of Massachusetts, a citizen of the 5 United States, have invented new and useful Improvements in Methods of Destroying Enemy Gun Positions, of which the following is a specification.

My invention relates to the destruction of 10 enemy gun positions and the like, and has for its object increased efficiency and effectiveness in accomplishing such destruction.

The drawing accompanying this specification shows, partly diagrammatically, means 15 for accomplishing this result.

Heretofore in warfare the reduction of land fortifications by battleships has been considered as substantially impossible and the results of such operations have been, as a 20 rule, substantially negligible, as, for example, in the Civil War, the Spanish-American War, and the attack on the Dardanelles in the recent war.

The method herein disclosed renders it 25 possible for the first time for naval forces to meet on a superior footing and to destroy land fortifications, such, for example, as those of the Dardanelles. It enables such reduction to be effected with great rapidity and 30 efficiency and it also is of great value in reducing land fortifications by means of siege artillery by shortening the time of reduction and the cost of said reduction. The method has numerous other advantages, some of 35 which are referred to in this specification.

Broadly speaking, this new method which forms the subject of the present application is the exact opposite of one of the two older methods heretofore used, as it is the exact 40 opposite to the desultory method, in which guns were fired at random intervals and at random targets and therefore exploded at random intervals and in random localities, in that in the new method the action is synchronous. Also it is the exact opposite to the 45 second of the old methods; *i. e.* the volley method, in that in the volley method a plurality of guns are fired simultaneously and not necessarily at the same target, and the 50 explosions take place more or less at random even when all are fired at the same target, on account of the dispersion of the volley making the times of impact different, whereas in the present method a plurality of guns

is not necessary, as a single gun may be used, 55 and if a plurality of guns are used they need not be fired simultaneously, and it is the explosion of the shells, which do not explode by impact but by time fuses, which occurs simultaneously, the shells all being fired into 60 a certain square and lying there embedded in the earth or concrete until the explosion time is reached, whereupon all explode simultaneously.

This method, as will be seen, is entirely 65 novel and has never before been used in warfare and, so far as applicant has been able to ascertain from the ordnance officers of the United States, Great Britain and France, has never been proposed.

The drawing illustrates suitable means for 70 utilizing the present invention. As is well known in warfare, the territory in the neighborhood of the fighting line, for example, that of the fortifications to be attacked, is 75 divided into squares of any suitable area. For example, in artillery work the squares may be twenty-five yards on the side. Such a square 11, in which the enemy's gun 12 is located, is shown in the figure.

The position of the enemy's gun 12 having 80 been located in the square 11 by any suitable means, it might be destroyed in the old well known way; *i. e.* the guns 19, 20, and 21 having been ordered to destroy it, commence to 85 throw shells into square 11 and continue until gun 12 is put of action. This old method, as a rule, requires a large number of shells. Immensely more powerful effects may be obtained by the use of applicant's 90 synchronized fuse method. In this method, instead of each gun firing independently of the other two, or all of the guns being fired in volleys with impact fuses, thereby necessarily exploding, except in rare instances, at 95 different times, in the new method the guns may be operated substantially independently of each other but the shells are arranged so that all shells which have fallen within the square 11 within a given period of time lie 100 there until a certain definite explosion time arrives, whereupon all explode simultaneously.

By this means immensely greater destructive effect can be obtained and the action of 105 the enemy's batteries greatly weakened for the following reasons.

With either of the older methods, *i. e.*

desultory firing or volley firing, and using the three guns, 19, 20, 21 (capable of being fired once per minute without becoming so heated as to spoil the rifling in long continued firing) the maximum number of shells which could be exploded per minute in the area 11 is three shells only; whereas by the method herein described the three guns may each fire say ten shells and the synchronized fuses may be arranged to act so that all thirty shells will explode simultaneously, say one minute after the last shell has fallen into the square 11. It is well known from experiment and theory that the simultaneous explosion of thirty shells, or charges of explosive, within a given area produces much greater destructive effect than the random non-simultaneous discharge of thirty shells within the same area.

As a recent illustration of this, the munition ship *Mt. Blanc* in Halifax Harbor produced a much greater destructive effect than if each single charge of explosive which the ship was carrying had exploded individually.

Applicant's experiments show that with the synchronized fuse method the destructive effect is approximately proportioned to the square of the number of shells exploded simultaneously.

Obviously a single gun operating this way can produce the same destructive effect as a large number of guns operating by volley firing or by random firing.

As the timing of the fuses is unknown to those operating gun 12, after the fall of the first shell in the area 11 the effect on the gun crew will be that all operations will be suspended until the explosion time has arrived and the shells have exploded, whereas in volley firing it is common practice to take cover at each volley and operate between volleys.

The method is obviously much less expensive for the production of a given effect and much quicker in operation.

In the use of applicant's method the shells will be equipped with time fuses, preferably a simple type clockwork mechanism such as that proposed by the applicant to the United States and British authorities at the commencement of the late war and which came into use and was found to be very reliable. The fuse time may be made as long as desired; and, in fact, the time may be so extended that four or five shells fired from a single gun may be arranged to explode simultaneously.

In operation, supposing that it is desired to explode thirty shells in one synchronized burst in the area 11, ten shells are laid out to each of the guns 19, 20, 21 and the clockwork time fuse of these shells may be all set simultaneously by any convenient means, for example, by a series electric circuit, to explode at fifteen minutes past zero time,

zero time being taken as the instant of simultaneous setting.

In addition to the clockwork mechanism the shells will be fitted with safety catches which prevent the operation of the firing mechanism of the clockwork fuse until the catch is sheared off by the shock of the explosion of the charge in the gun at the instant the shell is fired. This is called the safety.

The thirty shells having been set simultaneously for fifteen minutes past zero time, immediately after zero time each gun commences to fire the shells at the rate of say one a minute so that at the end of about eleven minutes all thirty shells will have been fired into the area 11 and may be buried in the dirt or concrete where they may lie until fifteen minutes from zero time, whereupon all thirty will explode simultaneously and do an immense amount of damage.

Incidentally, this long delay of the fuse time is an additional factor in producing large destructive effects, as after the shell has fallen dirt continues to fall into the hole the shell made while penetrating in the neighborhood, so that in effect each shell is tamped and, even acting independently, will produce a much greater effect than an impact shell or one fused to explode after penetrating a certain distance.

With the clockwork fuse referred to the explosion time can be definitely fixed to an accuracy of one one-hundredth of a second, which is more than ample to secure effective synchronization, since the rate at which an explosive wave travels through the ground is only of the order of a mile a second, so that in one one-hundredth of a second the distance traveled by the explosive wave will be less than twenty yards, while the area taken, 25 yards, is often smaller than would be used in practice.

If desired all guns may be fired simultaneously, by means of the firing circuits 22, 23; 22 being a battery and 23 a firing key located in said circuit. This is not, however, necessary.

This synchronized fuse method may of course be applied to effect the simultaneous discharge of shells under water as well as under ground; for example, by synchronizing the fuses of depth bombs.

In many cases, especially where depth bombs are used, it is advantageous to so direct the dropping of the depth bombs or shells that at the instant of firing they will all be located approximately on the arc of a circle whose center is at the point where the greatest effect is to be desired. In this way the explosion wave from the simultaneous discharge of the shells or depth bombs will arrive practically simultaneously at the center as at a focus, where the submarine or other body is which is to be de-

stroyed, and a greatly intensified effect will be obtained, since the destructive effect varies as the square of the amplitude of the explosive wave.

5 By the term "enemy gun position" is meant any position from which projectiles are discharged by the enemy.

By the term "explosive wave effects" is meant all the destructive effects resulting 10 from the simultaneous explosion of the synchronously time fused projectiles, *i. e.* not only from the fragments of the projectiles but also from the shock transmitted through the earth or water or air, from the 15 ejected dirt, stones, water, gases, etc., when synchronously exploded in the manner described.

What I claim is:

1. The herein described method of destroying enemy military positions which 20 consists in throwing into a predetermined and small area of said enemy military positions and at a distance from each other of the same order of magnitude as their depth 25 of penetration, an accumulation of time fused shells so set as to explode simul-

taneously and independently of their time of firing and of the distance at which they are fired, whereby the explosive wave effects from a number of said shells is made cumulative by occurring at the same instant, and independently of the number of guns from which the shells have been fired. 30

2. The herein described method of destroying enemy military positions which 35 consists in simultaneously setting the time fuses of an accumulation of time fused shells, whereby they will explode simultaneously and independently of their time of firing and the distance at which they are 40 fired; throwing said accumulation of shells into a predetermined and small area of said enemy military position and at a distance from each other of the same order of magnitude as their depth of penetration; whereby 45 by the explosive wave effects from said shells are made cumulative by occurring at the same instant and independently of the number of guns from which said shells have been fired.

REGINALD A. FESSENDEN.
